UNITED STATES PATENT OFFICE.

JOHN E. ROBERTS, OF ALBANY, NEW YORK.

COMBINATION HOME-ROUTE CARD AND EMPTY-CAR WAYBILL.

1,404,321.

Specification of Letters Patent. Patented Jan. 24, 1922.

Application filed April 20, 1921 Serial No. 462,892.

To all whom it may concern:

Be it known that I, JOHN E. ROBERTS, a citizen of the United States, and a resident of Albany, in the county of Albany and State of New York, have invented certain new and useful Improvements in Combination Home - Route Cards and Empty - Car Waybills, of which the following is a specification.

10 My invention relates to a combined home route card and empty car waybill, adapted for recording the status of all loaded foreign and private line cars received.

Heretofore separate cards have been employed for keeping the record of the movement of empty cars and the home route rights of such cars. It is the object of my invention to so combine these records that the subject matter will appear on one card 20 and the relationship of one part of the subject matter to the other is apparent and needs no further amplification.

Two distinct objects are accomplished by the use of my improved recording card, the 25 first of which is to indicate the connecting railroad from which the car was received and the second, for providing the necessary information for its empty movement.

The invention consists of a card provided 30 with printed matter and with blank spaces for the insertion of further record, so arranged as to indicate at any time the status and rights of the car to which the record appertains.

35 The manner in which my improved record card is used will be made more apparent in the accompanying specification and drawings, in which the figure shows a plan view of a card arranged in accordance with my 40 invention.

At the head of the card there is provided a section 10 with spaces for the insertion of data relative to the car and by which the car may be identified. This section has a 45 blank space 11 for the initials of the car, space 12 for the car number and a space 13 for an insertion indicating the kind of car.

Immediately below this there is provided a section 14 which is divided into one, two, 50 three or more sub-sections 15, the number being dependent on the circumstances prevalent on the railroad using this card. The section 14 is termed the empty car waybill and is used for recording information necessary in the movement of an empty car from 55 station to station.

On sub-section 15 is provided a number of blank spaces in which certain required information is adapted to be inserted. In space 16 is inserted the station to which the empty car is destined, in space 17 the order number, in space 18 the weight for engine rate, in space 19 the station from which the empty car was billed, in space 20 the name of the agent or yardmaster issuing the card 60 and in space 21 the date of its issuance.

A third section 22 is provided which contains printed matter listing the more important junction points such as indicated by the numeral 23. These junction points 70 are arranged in a column and immediately adjacent each junction point, such as indicated at 24, there is indicated the connecting railroads through which connection is made with this particular junction point. This 75 list of the connecting railroads are also arranged in a column. A column of blank spaces 25 are disposed adjacent the column of connecting railroads and provided with a heading "Date." In this column headed 80 "Date" and opposite the junction and proper connecting railroad is to be inserted the date a car was received, which information is necessary to indicate the junction point and road via which the car has rights for movement en route home to the owning road.

A number of blank spaces 26 may be provided at the base of the three columns just described in order to provide space for the insertion of the name of the junction point, 90 railroad received from and date in case the list of junction points and connecting railroads does not include such junction point and connecting railroad.

The printed matter described which 95 shows the junction points and connecting railroads are in each instance arranged in accordance with the particular railroad using the car. It is obvious that this portion of the card will be different and peculiar to 100 the system of the particular road using the card. On receipt of a car under load from a connecting line, the identification section 10 of the card is filled out by inserting in the proper places the car initials, number, kind 105 and class of car. In the home route section 22 in the proper space opposite the junction at which the car was received and the road from which the car was received, the date of receipt is entered. The card is then attached to the revenue waybill and travels 110 with it to the destination or junction point

if the car is for delivery to a connecting railroad. If the car is destined for unloading at a point on the road using the car, this card is filed and the information shown 5 thereon used as a basis for disposing of the car, either loaded or empty in accordance with the Car Service Rules and Practices. In the event that the car is re-loaded, the card serving in the capacity of a home route 10 card only, is attached to the new billing and travels with it to its new destination.

When it is desired to move the car empty to any point, the first section 15 of the empty car waybill is properly filled out, thereby 15 indicating the station to which the car is destined, order number, weight for engine rating, station billed from, agent or yard-master issuing card and the date of its issuance. The car may, therefore, be forwarded 20 without the necessity of issuing a separate empty car waybill to cover its movement. If the car is later re-loaded the agent loading the same is held responsible for cancelling the used section of the empty car 25 waybill which had been previously filled out to cover its movement while empty to his station.

When the car is loaded and destined to a point on another railroad the combination 30 home route card and empty car waybill is separated from the revenue waybill at the junction point where delivery is made to the connecting railroad and filed, pending probable return of the car. If the car is ultimately returned loaded, it is then matched up with the billing and securely attached to it and travels with the car to its new destination or junction point. If however, the car 35 is returned empty, the proper spaces are 40 filled out in the next sub-section 15 of the empty car waybill section from information obtained from a home route section 22 and the car becomes immediately available for movement.

Consequently, it will be seen that a car 45 while travelling on the railroad issuing this record card is accompanied by the same upon either an empty or loaded movement. If the car is delivered to a connecting line 50 other than the one it was originally received from, it is handled as previously explained. The issuance of a particular card identified 55 with and used as a record for a particular car, not having ceased to exist until the car is returned to the road from which it was originally received. When, however, such delivery has been accomplished the card is 60 filed at the delivering junction point or forwarded to the General Car Service Office where it may be examined to ascertain that the car has been efficiently and properly handled and in full accord with the existing 65 Car Service Rules.

The advantage obtained by the use of my improved combination record card is obvious. The arrangement is such that the relationship of one record to the other is apparent and does not have to be written out. Ordinarily it has been a practice at both destination and junction stations to issue 70 separate empty car waybills provided with each individual movement of the car to which was attached a card showing the home route of the car. A combination card such as hereinbefore described eliminates the use 75 of an additional card and facilitates the handling of this necessary record at all points, thereby effecting a decided saving of time, labor and expense.

Having thus described my invention, what 80 I claim is:

1. A record card for recording home route rights and empty car movements of railway cars provided with an appropriately designated identification section, an appropriately designated empty car waybill section divided into a multiplicity of sub-sections in combination with a home route section, in which are listed the principal junction points and connecting railroads, of the 90 home route, whereby the empty car waybill data and home route rights of a car will be simultaneously apparent.

2. A record card for recording the empty car movements and home route rights of 95 railway cars, provided with an identification section containing blank spaces for data by which a car may be identified, an appropriately designated empty car waybill section immediately thereunder, provided with a multiplicity of sub-sections, each sub-section having blank spaces for insertion of the station to which the empty car is billed, the order number, its weight for engine rating, station billed from, signature of agent, and date of its movement and a home route section upon which are listed in a column the junction points of the home route, adjacent each junction the lines connecting said junctions, and a column of 110 blank spaces adjacent the column of lines for the insertion of the date a car is received, all substantially as and for the purpose described.

3. A record card of the class described 115 provided with an appropriately designated section for the insertion of identification data, an appropriately designated section for the insertion of data indicating the empty movements of a car, in combination 120 with an appropriately designated section in which may be indicated the home route rights of the car, said sections being permanently associated so that empty car movement data will be simultaneously apparent. 125

JOHN E. ROBERTS.
